LIQUID GAS BURNER

Sigmund Klose, Flushing Heights, and Alexander J. Turpin, Stewart Manor, N. Y., assignors to Hauck Manufacturing Co., Brooklyn, N. Y., a corporation of New York

Application March 26, 1956, Serial No. 573,911

10 Claims. (Cl. 158—53)

This invention relates to burners, particularly for bottled liquid petroleum gas.

Portable burners have heretofore been made using a liquid fuel such as kerosene. More recently efforts have been made to use L. P. gas, that is, liquified petroleum gas such as propane, butane, or other bottled gas, these being bottled under pressures so high that the gas is in liquid form. Bottled gas has important advantages, such as easy operation of the burner; high efficiency; safety, in that there is no liquid fuel to spill or catch fire; full range of heat adjustment without need for removing the burner, as from a melting kettle; clean operation without smoke or soot; no need for pumping up pressure in the fuel tank by means of a hand pump; and no need for preheating, so that there is no loss of light-up time.

However, attempts to use bottled gas at high rates have led to new difficulties. The expansion or vaporization from liquid to gas at the surface of the liquid has a refrigerating action. A heavy layer of frost may appear on the outside of the bottle up to the liquid level in the bottle. The expansion reduces temperature to the point where only slow further volatilization takes place. This reduces the flow of gas, to overcome which it has been sought to use two bottles or even three or more bottles connected in parallel, in an effort to maintain adequate flow of gas.

The primary object of the present invention is to overcome the foregoing difficulty, and to make it possible to work with a single bottle. A more particular object is to provide comparatively simple apparatus for the purpose, requiring only an expansion valve and an extra pipe and a regenerative type heating means at the burner. However, we have found that the mere provision of ordinary regenerative heating is not enough, and in accordance with features and objects of the present invention we apply heat to the expanded gas immediately following the expansion valve, this heat being applied either by heat exchange or by direct mixture of heated gas with the chilled gas, or more preferably both.

To accomplish the foregoing general objects, and other more specific objects which will hereinafter appear, our invention resides in the liquid gas burner elements, and their relation one to another, as are hereinafter more particularly described in the following specification. The specification is accompanied by a drawing, in which:

Fig. 1 is a partially sectioned view showing a liquid gas bottle and burner assembly embodying features of our invention;

Fig. 2 is an enlarged view of the burner assembly with most of the structure shown in vertical section;

Fig. 3 is a transverse section taken approximately in the plane of the line 3—3 of Fig. 2;

Fig. 4 is a side elevation of a modification;

Fig. 5 is a fragmentary vertical section through the spud holder and longitudinally of the modification; and

Fig. 6 is a fragmentary transverse section taken in the plane of the line 6—6 of Fig. 5.

Referring to the drawing, and more particularly to

2

Fig. 1, a tank or so-called "bottle" of liquified gas is shown at 12. In lieu of a gas shut-off valve located directly at the top of the bottle, we employ a dip tube 14 extending all the way down to the bottom of the bottle.

For convenience a shut-off valve 16 may be provided at the top of the dip tube 14, but this valve is not used as an expansion valve. Its purpose is merely to control the flow through hose 18 of liquid gas which is still in liquid form. The hose 18 is a high pressure hose capable of withstanding the pressure in bottle 12, which may be about 125 lbs. per square inch. Even a very slow vaporization of the liquid gas at the top of the bottle, suggested here by the space 20, is ample to insure delivery of liquid gas upward through dip tube 14 to pipe 18, and there is no problem of refrigeration.

15 The burner assembly comprises a spud 22, a nozzle 24, and a regenerative heating jacket 26 associated with or located within the nozzle 24. There is also a pipe 28 acting as a handle for the burner proper. These burners are frequently used in melting kettles, and in such case 20 may be dropped down into a well leading to a flue at the bottom of the kettle, and the length of pipe or handle 28 is determined largely by the depth of the well in the kettle.

An expansion valve 30 is located at the upper or remote end of pipe 28. The expanded gas is first supplied 25 to the jacket 26, and thence from the jacket 26 to the spud 22. In the present case the supply to jacket 26 is through a bottom pipe 32, and the supply from jacket 26 to the spud 22 is through a top pipe 34.

As so far described the arrangement would resemble 30 that of an ordinary regenerative burner, but we have found that it is important to heat the expanded gas in the region immediately following the expansion valve 30. For this purpose we provide a second pipe which is most conveniently disposed concentrically within the 35 handle pipe 28, as is indicated by the dotted lines 36. The heated gas leaving regenerative jacket 26 through pipe 34 is connected not only to the spud 22, but also to one of the pipes 28, 36, while the expanded and therefore chilled gas leaving the valve 30 flows through the 40 other pipe. In the present case the chilled gas flows through the inner pipe 36, while the heated gas is connected to the outer pipe 28. Moreover, in preferred form some of the heated gas is actually mixed with the chilled gas immediately following the expansion valve.

45 Referring to Fig. 2 of the drawing, the expansion valve 30 is a needle valve having a valve stem 40 terminating in a conical point at 42. The usual valve seat is replaced by a special seat 44 which is secured to the upper end of the inner pipe 36. The pipe 36 is preferably made of 50 brass. The upper end of pipe 36 has holes or ports 46 therein. These admit some of the heated gas into pipe 36, for direct mixture with the chilled gas.

At its lower end the inner pipe 36 fits into a passage 55 48 drilled in a spud holder 50 which carries the spud 22. Passage 48 turns at 52 to the horizontal pipe 32 leading to the heating jacket 26.

As here shown the nozzle 24 is cylindrical, and the heating jacket 26 is formed by another cylindrical wall 54 60 of somewhat smaller diameter disposed concentrically within the rear portion of nozzle 24. The space between the cylinders is sealed by a circular line of welding shown at 56, and to facilitate the welding operation an annulus of wire 58 may be forced into the space between 65 the cylinders to act as an end wall before beginning the welding operation to seal all three parts together.

The rear end of the heating jacket 26 is similarly closed by arcuate wire indicated at 60, and by welding indicated at 62, but in this case two curved pieces of wire are 70 used, each less than a semi-circle in length, in order to leave a space or opening at the top and at the bottom.

These are best shown in Fig. 3. The upper horizontal pipe 34 is welded at its forward end to the upper rear edge of the jacket, and the horizontal lower pipe 32 is welded at its forward end to the bottom rear edge of the jacket. The welding is such as to seal the jacket and yet to provide flow communication between the pipes and the space inside the jacket.

Reverting to Fig. 2, the rear end of the upper horizontal pipe 34 is connected to the spud block 50, as shown at 68, and the block has passages 70 and 72 leading to the spud 22 and thus supplying heated gas to the spud. However, the passage 70 is continued rearwardly to provide communication with the outer pipe 28, or, more specifically, with the jacket space 74 between the pipes 36 and 28. The spud holder 50 in the present case is a generally upright block of metal such as cold rolled steel, and the passages 48, 52, 70 and 72 are formed by drilling the block. In such case the upper end of passage 72 may be sealed, as by driving a ball or plug 76 into the passage and welding thereover, as shown at 78.

It is desirable to provide for adjustable air supply, and for this purpose an air adjusting sleeve 80 is made movable toward or away from the spud 72. The sleeve 80 is preferably made slightly larger in diameter than the nozzle 24, and is slideable thereover. The sleeve may be provided with guides 82 and 84 which are slideable on the horizontal pipes 32 and 34, respectively. The sleeve may additionally be provided with a set screw 86 bearing against the pipe 34 to lock the sleeve in adjusted position.

The burner elements may be mounted on a suitable base 88, which in the present case is bent up out of sheet metal, as shown in Fig. 3. The sides of the nozzle 24 are welded to the forward end of the base, as indicated at 90 in Fig. 2.

It will be understood that it is not essential for the handle pipe 28 to extend upward from the burner. When the burner is to be used in a bottom fired melting kettle, or is to be used for some other purpose in which the handle is preferred to be behind the burner, the parts may be disposed in that fashion, as illustrated in Figs. 4, 5 and 6 of the drawing. Referring to those figures, the burner, generally designated 92, corresponds in substantially all respects to that previously described, except that the handle pipe 94 is disposed horizontally and extends rearwardly from the spud holder block 96. The expansion valve 98 is preferably connected to the hose 100 through an elbow 102.

Referring now to Fig. 5, the spud block 96 receives the spud at 104, and has gas passages 106 and 107 which correspond generally to the passages 52 and 70 previously described, and which similarly receive horizontal pipes leading to the regenerative heating jacket. However, the vertical passage 110 terminates short of the top of the block, and receives the inner handle pipe 112, as shown. The horizontal passage 114 is connected not only to the intersecting vertical passage 108, but also leads to the space 116 between the outer handle pipe 94 and the inner handle pipe 112.

The outer handle pipe is preferably expanded vertically and flattened sidewardly somewhat, as shown at 118 in Fig. 6. This gives more room for a flow connection with passage 114, and it helps make the connection between the handle 94 and the spud block 96 more rigid. This connection is by welding, indicated at 120 in Fig. 5.

It will be understood that while we have shown the handles 28 (Fig. 1) and 94 (Fig. 5) substantial in length, this is not essential for successful operation of the burner assembly. One reason is that the ports 46 (Fig. 2) afford a direct admixture of some of the heated gas with the chilled gas, and this alone eliminates freezing of moisture. From this view point the heat exchange function of the concentric pipes is not important. It may be mentioned that a definite dependable flow of heated gas through

the ports 46 is assured because there is an aspirating or venturi action caused by the rapid flow of the expanded gas immediately following the expansion valve, and this draws some of the heated gas along with it.

With this in mind it will be understood that it is not essential to have a long handle pipe or even any handle pipe, and instead the connection between the expansion valve and the spud holder may be reduced to a matter of only a few inches in length. It is not essential to use concentric pipes in the handle, and instead two collateral pipes may be employed, one for the chilled gas, and the other for the heated gas. In such case, of course, there is no heat exchange action, but there is a mixture of hot gas with the chilled gas to prevent freezing of moisture.

It is believed that the construction and operation, as well as the advantages of our improved liquid gas burner, will be apparent from the foregoing detailed description. One advantage is that the burner may be lighted and the flame immediately adjusted to desired dimension by manipulation of the valve, without waiting through a long preheating period for the flame to stabilize, as has been found necessary with kerosene or like liquid fuel. A workman may light and adjust the present burner, and promptly walk away from it.

The reason is that in the present case the regenerative heating is needed only to counteract the refrigerant action, and the latter takes time to build up. Thus when the burner is first lighted there may be no appreciable regenerative heat, but there also is no appreciable chilling or frost. By the time the latter builds up, the regenerative heat has also built up.

Another advantage is that the heating jacket for the chilled gas acts reciprocally as a cooling means for the cylindrical flame holder or nozzle. The nozzle may operate at red heat, and without some cooling means tends to be burned away. However, when the nozzle is intimately associated with a heat exchanger receiving the chilled gas it is protected against excessive heating.

The regenerative heater of the burner need not be made up of concentric cylinders, and other forms of heat exchanger may be used, as for example, a helical heating coil. The helix may be tight enough to act as a nozzle, or it may be disposed in direct contact with a nozzle.

Inasmuch as regenerative burners are themselves in wide use, it may be said that our improved burner solves a heretofore difficult and troublesome problem of frost generation by the mere addition of one extra handle pipe, together with a rather convenient location of the expansion valve on the handle pipe.

It will be understood that while we have shown and described our invention in several preferred forms, other changes may be made in the structures shown, without departing from the scope of the invention, as sought to be defined in the following claims. In the claims the term "regenerative heating jacket" is intended to mean any form of heater at or near the burner flame, whether a coil or concentric cylinders or the like. The term "heating jacket" is used, instead of some other term such as "heat exchanger," merely to differentiate more readily from the concentric handle pipes. The term "nozzle" refers to any device for flame retention. The term "spud" refers to the discharge orifice where the gas is liberated to the atmosphere for ignition, and the orifice need not be in a separate plug-like member, as here shown, although that is a convenient and customary construction.

We claim:

1. A liquid gas burner assembly comprising a burner including a spud, and a regenerative heating jacket disposed in front of and spaced from said spud and heated by the flame from said spud, a first pipe connected to said burner, a liquid gas expansion means having a constricted orifice located at the end of and discharging in the form of a jet into said first pipe remote from said burner, means flow-connecting said pipe to the heating jacket inlet in

order to heat the already expanded gas, means connecting the outlet of said heating jacket to said spud in order to supply heated gas to said spud for combustion, means also connecting the outlet of said heating jacket to a second pipe, and means connecting said second pipe to said first pipe near the expansion means, whereby some of the heated gas is aspirated into and mixed with the expanded gas leaving the expansion means in gaseous state at a point near the expansion means and flows with the expanded gas on its way to the heating jacket, in order to help counteract the refrigerating effect of the expansion means.

2. A liquid gas burner assembly comprising a burner including a spud, a nozzle and a regenerative heating jacket disposed in front of and spaced from said spud and heated by the flame from said spud, an outer pipe connected to said burner, an inner pipe extending through the outer pipe, a liquid gas expansion means having a constricted orifice located at the end of said pipes remote from said burner and discharging in the form of a jet into one of said pipes, means flow-connecting said latter pipe to the heating jacket in order to heat the already expanded gas, means connecting the outlet of said heating jacket to said spud in order to supply heated gas to said spud for combustion, and means also connecting said heating jacket outlet to the pipe other than the one having the expansion means, said inner pipe having one or more ports near the expansion means, whereby some of the heated gas is aspirated into and mixed with the expanded gas leaving the expansion means in gaseous state at a point near the expansion means and flows with the expanded gas on its way to the heating jacket, in order to help counteract the refrigerating effect of the expansion means.

3. A liquid gas burner assembly comprising a burner including a spud, a nozzle and a regenerative heating jacket disposed in front of and spaced from said spud and heated by the flame from said spud, an outer pipe of appreciable length connected to said burner, an inner pipe extending through the outer pipe, a liquid gas expansion valve having a constricted orifice located at the end of said pipes remote from said burner and discharging in the form of a jet into one of said pipes, means flow-connecting said latter pipe to the heating jacket in order to heat the already expanded gas, means connecting the outlet of said heating jacket to said spud in order to supply heated gas to said spud for combustion, and means also connecting said heating jacket outlet to the pipe other than the one having the expansion valve, whereby the pipes act as a heat exchanger to heat the expanded gas leaving the valve at a point near the valve, said inner pipe having one or more ports near the expansion valve, whereby some of the heated gas is aspirated into and mixed with the expanded gas leaving the valve at a point near the valve and flows with the expanded gas on its way to the heating jacket, in order to help counteract the refrigerating effect of the expansion valve.

4. A liquid gas burner assembly comprising a burner including a spud, and a nozzle for the flame produced by said spud, at least part of said nozzle being double walled to provide a heating jacket, an outer pipe rigidly secured to said burner, an inner pipe extending through the outer pipe, a liquid gas expansion valve having a constricted orifice located at the end of said pipes remote from said burner and discharging in the form of a jet into the inner pipe, means flow-connecting the inner pipe to the heating jacket in order to heat the expanded gas, means connecting the outlet of said heating jacket to said spud in order to supply heated gas to said spud for combustion, and means also connecting said heating jacket outlet to the outer pipe, said inner pipe having one or more ports near the expansion valve, whereby some of the heated gas is aspirated into and mixed with the expanded gas leaving the valve at a point near the valve and flows with the expanded gas on its way to the heat-

ing jacket, in order to help counteract the refrigerating effect of the expansion valve.

5. A liquid gas burner assembly comprising a burner including a spud, a nozzle for the flame produced by said spud, at least part of said nozzle being double walled to provide a heating jacket, and an air sleeve slidable on said nozzle to adjust the same relative to the spud, an outer pipe of appreciable length rigidly secured to said burner, an inner pipe extending through the outer pipe, a liquid gas expansion valve having a constricted orifice located at the end of said pipes remote from said burner and discharging in the form of a jet into the inner pipe, means flow-connecting the inner pipe to the heating jacket in order to heat the expanded gas, means connecting the outlet of said heating jacket to said spud in order to supply heated gas to said spud for combustion, and means also connecting said heating jacket outlet to the outer pipe, whereby the pipes act as a heat exchanger to heat the expanded gas leaving the valve at a point near the valve, said inner pipe having one or more ports near the expansion valve, whereby some of the heated gas is aspirated into and mixed with the expanded gas leaving the valve at a point near the expansion valve and flows with the expanded gas on its way to the heating jacket, in order to help counteract the refrigerating effect of the expansion valve.

6. A liquid gas burner assembly comprising a spud holder, a spud carried thereby, a nozzle for the flame produced by said spud, said nozzle being disposed in front of and spaced from said holder, a wall concentric with and spaced from said nozzle and forming therewith a regenerative heating jacket which is heated by the flame from the spud, an outer pipe of appreciable length acting as a handle and rigidly secured to said holder, an inner pipe extending through and spaced within the outer pipe to form a passage therebetween, a liquid gas expansion valve located at the end of said pipes remote from said holder and discharging into one of the concentric pipes, a horizontal pipe extending from the holder to the jacket, a passage through the holder connecting the aforesaid gas receiving concentric pipe to said horizontal pipe, another horizontal pipe extending from the holder to another part of the jacket, and passages in the holder connecting said last mentioned pipe to the other concentric pipe and to the spud in order to supply warmed gas to said spud for combustion.

7. A liquid gas burner assembly comprising a spud holder, a spud carried thereby, a nozzle for the flame produced by said spud, said nozzle being disposed in front of and spaced from said holder, a wall concentric with and spaced from said nozzle and forming therewith a regenerative heating jacket which is heated by the flame from the spud, an outer pipe of appreciable length acting as a handle and rigidly secured to said holder, an inner pipe extending through and spaced within the outer pipe to form a passage therebetween, a liquid gas expansion valve located at the end of said pipes remote from said holder and discharging into one of the concentric pipes, a horizontal pipe extending from the holder to the jacket, a passage through the holder connecting the aforesaid gas receiving concentric pipe to said horizontal pipe, another horizontal pipe extending from the holder to another part of the jacket, and passages in the holder connecting said last mentioned pipe to the other concentric pipe and to the spud in order to supply warmed gas to said spud for combustion, said inner pipe having one or more ports near the expansion valve whereby some of the heated gas is mixed with and flows with the expanded gas.

8. A liquid gas burner assembly comprising a spud holder, a spud carried thereby, a nozzle for the flame produced by said spud, said nozzle being disposed in front of and spaced from said holder, a wall concentric with and spaced from said nozzle and forming therewith a regenerative heating jacket which is heated by the

flame from the spud, an outer pipe of appreciable length acting as a handle and rigidly secured to said holder, an inner pipe extending through and spaced within the outer pipe to form a passage therebetween, a liquid gas expansion valve located at the end of said pipe remote from said holder and discharging into one of the concentric pipes, a horizontal pipe extending from the holder to the jacket, a passage through the holder connecting the aforesaid gas receiving concentric pipe to said horizontal pipe, another horizontal pipe extending from the holder to another part of the jacket, and passages in the holder connecting said last mentioned pipe to the other concentric pipe and to the spud in order to supply warmed gas to said spud for combustion, said inner pipe having one or more ports near the expansion valve whereby some of the heated gas is mixed with and flows with the expanded gas, and an air adjusting sleeve movable toward and away from the holder, said sleeve having guide means sliding on the aforesaid horizontal pipes.

9. A liquid gas burner assembly comprising a spud holder block, a spud carried thereby, a cylindrical nozzle for the flame produced by said spud, said nozzle being disposed in front of and spaced from said block, another cylindrical wall concentric with and spaced from said nozzle and forming therewith a regenerative heating jacket which is heated by the flame from the spud, an outer pipe of appreciable length acting as a handle and rigidly secured to said block, an inner pipe extending through and spaced within the outer pipe to form a passage therebetween, a liquid gas expansion valve located at the end of said pipes remote from said block and discharging into the inner pipe, a horizontal pipe extending from the block to the bottom rear edge of the jacket, a passage through the block connecting the aforesaid inner pipe to said horizontal pipe, another horizontal pipe extending from the block to the rear top edge of the jacket, and passages in the block connecting said pipe to the spud

to feed warmed gas to the outer pipe and to the spud in order to supply warmed gas to said spud for combustion.

10. A liquid gas burner assembly comprising a spud holder block, a spud carried thereby, a cylindrical nozzle for the flame produced by said spud, said nozzle being disposed in front of and spaced from said block, another cylindrical wall concentric with and spaced from said nozzle and forming therewith a regenerative heating jacket which is heated by the flame from the spud, an outer pipe of appreciable length acting as a handle and rigidly secured to said block, an inner pipe extending through and spaced within the outer pipe to form a passage therebetween, a liquid gas expansion valve located at the end of said pipes remote from said block and discharging into the inner pipe, a horizontal pipe extending from the block to the bottom rear edge of the jacket, a passage through the block connecting the aforesaid inner pipe to said horizontal pipe, another horizontal pipe extending from the block to the rear top edge of the jacket, and passages in the block connecting said pipe to the spud in order to supply warmed gas to said spud for combustion, said inner pipe having one or more ports near the expansion valve whereby some of the warmed gas is mixed with and flows with the expanded gas.
